(57) **CLAIM**

The ornamental design for a glare visor, as shown and described.

DESCRIPTION

FIG. 1 is a perspective view embodying the ornamental design of the glare visor constituting my invention and shown in use against a window in a vehicle.;

FIG. 2 is an enlarged front plan view of the glare visor shown in FIG. 1;

FIG. 3 is a right side edge view of FIG. 2;

FIG. 4 is a bottom side edge view of FIG. 2;

FIG. 5 is an enlarged rear plan view of the glare visor shown in FIG. 2;

FIG. 6 is a right side edge view of FIG. 5; and,

FIG. 7 is a top edge view of FIG. 2.

The broken line showing of the environment is for illustrative purposes only and forms no part of the claimed design.
